DESIGN FOR A RANGE

Edwin R. Culver, Jr., St. Louis, Mo.

Application February 7, 1941, Serial No. 98,832

Term of patent 7 years

To all whom it may concern:

Be it known that I, Edwin R. Culver, Jr., a citizen of the United States, residing in the city of St. Louis and State of Missouri, have invented a new, original, and ornamental Design for a Range, of which the following is a specification, reference being had therein to the accompanying drawing, forming part thereof.

In the drawing:

Fig. 1 is a perspective view of a range showing my new design, and

Fig. 2 is a top plan view thereof with the warming oven shown in Fig. 1 omitted.

The two sides of the range are identical in appearance.

The dominant features of the design reside in the portions shown in full lines.

I claim:

The ornamental design for a range, as shown and described.

EDWIN R. CULVER, JR.
